UNITED STATES PATENT OFFICE.

JOSEPH VOGT, OF NEW YORK, N. Y.

WALL-PAPER SEAM-CUTTING AND PASTING MACHINE.

SPECIFICATION forming part of Letters Patent No. 742,808, dated October 27, 1903.
Application filed June 30, 1903. Serial No. 163,724. (No model.)

To all whom it may concern:

Be it known that I, JOSEPH VOGT, a citizen of the United States of America, and a resident of New York, in the county and State of New York, have invented certain new and useful Improvements in Wall-Paper Seam-Cutting and Pasting Machines, of which the following is a specification.

This invention has reference to a novel wall-paper pasting and seam-cutting machine particularly designed for the purpose of cutting the seams and pasting the wall-paper in one operation.

It is a feature of this invention to produce a device by means of which a great deal of time is saved and a certain amount of work done in half the time formerly used.

By means of this machine the back of the wall-paper is covered with paste very uniformly. The even coating of paste on the back of the wall-paper as produced by this device can never be obtained by means of brushes no matter whether operated by hand or forming part of a machine.

The invention is illustrated in the accompanying drawings, in which—

Figure 1 is a side elevation of the machine which embodies my invention. Fig. 2 is a cross-section on line 2-2 of Fig. 3. Fig. 3 represents the machine in top plan view partly broken away. Fig. 4 illustrates in detail view the adjustment of the stationary cutter-blades, and Fig. 5 is a detail view of a paste-roll bearing.

Similar characters of reference denote like parts in all the figures.

In the drawings, *a* represents an oblong rectangular box, preferably made of wood, whose long sides *a'* *a''* are of such length as to suit the width of the wall-paper as it is bought in the market. The inner portion of the box forms a continuous liquid-tight vessel, in and on which the mechanical parts of the device are mounted. The rear bottom portion of the box forms a separate space *b* by means of a partition *b'*. (Shown in Fig. 2.) This space extends through the entire length of the box and serves as the receptacle for the roll of wall-paper to be passed through the machine.

There are two sets of rollers in the box, which are rotated by a drive-wheel with crank-han-

dle and gears. These rollers may be made of wood or any other suitable material. I prefer, however, to make them of seamless steel tubing for the purpose of having them durable and light. One set of rollers *r* *r'* are located in the rear top portion of the box. These rollers serve as guiding-rollers for the wall-paper after same is drawn out from the space *b*. If desired, the rollers *r* *r'* may be covered with strong canvas for better guiding particularly thin wall-paper. The second set of rollers consists of the three rollers *r*² *r*³ *r*⁴. The rollers *r*³ *r*⁴ are located within the box. These two rollers are quite a distance apart, the top roller *r*³ being practically in one horizontal plane with the roller *r'*, while the roller *r*⁴ is located near the bottom of the box, as is shown in Fig. 2. The rollers *r*³ *r*⁴ are connected by an endless piece *c* of heavy cloth or other suitable material which is capable of taking up paste. This endless piece of cloth *c* extends over the entire length of the rollers *r*³ *r*⁴. The top roller *r*² is practically in contact with the endless piece of cloth, so that the roller *r*³ and the single roller *r*² form another pair of guiding-rollers for the wall-paper *w*. After passing the rollers *r*² *r*³ the wall-paper slides on the guides *d* and passes through the opening *o* in the long side wall *a'*. 8c

As above mentioned, the rollers are rotated by means of a drive-wheel *e*, provided with a crank-handle *f*. (See Figs. 1 and 3.) The drive-wheel *e*, as well as the gears for the rollers, is located outside of the box on the small side *a*³. The drive-wheel is mounted on a strong metal bar *h*, having two rectangular ends *h'*, by means of which it is secured on the box. The inner end of the shaft *e'* of the drive-wheel is located in a bearing in the side *a*³ of the box while the other end passes through the bar *h* and connects then with the crank-handle. Between the drive-wheel *e* and the inner side of the bar *h* a small ratchet-wheel *e*² is provided, in which reaches a spring-pawl *e*³, so arranged that the drive-wheel cannot be turned backward. The spring-pawl *e*³ is secured on the inside of the bar *h*. The trunnion of each of the four rollers located on the side *a*³ of the box is provided with a tooth-wheel *t* *t'* *t*² *t*³, designated correspondingly to the rollers *r* *r'* *r*² *r*³. The tooth-wheels *t* and 9c 10c

t^3 engage the drive-wheel e , one being located on each side of same. The tooth-wheel t is driven by the tooth-wheel t' and gears with same, while the tooth-wheel t^2 gears with the tooth-wheel t^3 and is rotated thereby. It is plainly understood that upon turning the crank-handle the four rollers will rotate by means of the gears just described, while the bottom roller r^4 will rotate by the motion of the roller r^3 by means of the endless piece of cloth passing over both. The rollers in connection with these gears rotate likewise, and the wall-paper is moved along thereby during the operation of the apparatus.

15 The two top rollers r r^2 , with the tooth-wheels t t^2 thereon, are mounted on a special rectangular and oblong frame g . (Shown in Figs. 1 and 2, and particularly in Fig. 3.) This frame is hinged on the small side a^4 of the box, while in the front it is so arranged that it can be lifted up with the rollers r r^2 and their tooth-wheels t t^2 and other parts of the apparatus mounted thereon, which will be described farther on. This is done for the purpose of cleaning the machine easily, and particularly the endless piece of cloth on the rollers r^3 r^4 . After the two rollers r r^2 are out of the way the roller r^3 may be conveniently removed. The end of this roller on the side a^4 is provided with a spring-bearing i of usual construction, as is shown in detail in Fig. 5. The spring-bearing may be easily withdrawn and the roller taken out. The bottom roller r^4 rests on one side in a bearing j , which is sidewise open, as is shown in Fig. 2, and therefore is easily removed after the roller r^3 has been removed. In this manner all the rollers are out of the way and the box can be cleaned and the cloth washed before the paste gets dry thereon.

16 The mechanism for cutting the seams of the wall-paper is located on the top frame g . Near the roller r there is secured a metal bar k , (see Fig. 3,) which is permanently secured to the frame g . This bar has a rectangularly-bent portion on the side where the gears are located, and the other end is secured to a metal piece on the frame g , so that it is somewhat elevated. The seam-cutting devices are attached to this bar. The bar with the cutting devices is lifted up with the top rollers when the frame g is raised, as above described. The bar is provided with a number of incisions k' , in which the cutting devices are secured, as is shown in detail in Fig. 4. Each cutter proper consists of a rotatable disk l , mounted in a fork-like frame m , which has a forward extension m' . On the shaft of the cutting-disk l is secured a pinion n , and on the extension m' of the fork-like frame m is secured another pinion n' , (see Fig. 2,) which gears with the pinion n . The roller r has gears p on its top surface opposite the openings k' in the bar k , so arranged that upon turning the crank-handle, and thereby the rollers, the pinion n' will be ro-

tated by means of these gears p , and thereby the pinion n and the cutting-disk l . After being mounted in the proper position the cutting devices are secured in the openings k' by means of a set-screw q .

In addition to each cutting-disk l there is a stationary cutter-blade s . These blades are adjustably mounted on a movable iron bar u , located on the top inside wall a^2 of the box. The cutter-blades rest on a rectangular piece of galvanized-iron sheeting v , which is secured to the wall a^2 below the iron bar u and extends over to the roller r' , as is shown in Fig. 2. The end of the bar u which is located on the wall a^4 of the box rests against a spring u' . The other end is connected to a metal handle x , pivoted to the wall a^3 of the box and so arranged that by pushing the handle out or away from the box the bar u , with the stationary cutter-blades thereon, is moved somewhat in, forcing the spring back and the stationary blades away from the cutter-disk. This is done when it is desired to lift the frame g for the purpose of clearing the cutting-disks, which are raised with the frame. When the frame is lowered and down on the box, then the handle or lever x is turned in, whereby the bar u moves toward same and the cutter-blades rest close to the cutting-disk, the spring u' keeping them in that position. This handle or lever x has an extension x' , (shown in Fig. 4,) which rests on the bar of the frame g near the gears, and thereby keeps the frame down during the operation of the machine. The stationary cutter-blades are adjustable, each having a slot in the portion which rests on the bar u , and a screw tightens them to said bar; but this is not shown on the drawings. When the screw is loosened, then the blade may be shifted to the right or left and the screw then tightened, when the blade is in the desired position.

Several cutting devices are provided. The two devices on the ends of the bar h serve for cutting the seams of the wall-paper, while the cutting devices located between the two are used for cutting the seams of borders. As the borders are of different width, some being three inches wide, while others are six, nine, twelve, it is necessary to have several cutters for borders on the machine.

When the machine is to be used, the paste y is poured into the box, as is shown in Fig. 2, and the wall-paper located in the space b run through the machine. It meets first the cutting devices, where the seams are cut off. Then it passes through the guiding-rollers r r' and then between the rollers r^2 r^3 . The back of the paper comes there in contact with the endless cloth which carries the paste and is thereby pasted. The paper then slides along the guides d through the opening o and leaves the machine. A small table a^5 is hinged to the wall a^4 of the box, (shown in Figs. 1 and 2,) which is let down on the hinges when the machine is used. The pasted wall-paper leav-

ing the machine is collected on the table in such a manner that only the pasted portions come in contact with each other. This is easily done, because when the paper is pasted 5 and wet on the back it gets quite heavy and sinks down. It is then conveniently folded in the described manner.

Most of the rooms are twelve to fifteen feet high. It is therefore desirable to know when 10 this number of feet of paper has been pasted by the machine. For this purpose there is provided on the frame g above the drive-wheel e an indicator z , of suitable construction. (Shown in Figs. 1 and 3.) This indicator 15 is provided with a small pinion z' , which gears with the drive-wheel and moves the hand z^2 thereon. Each graduation-mark on the dial z^3 represents a foot. When the desired number 20 of feet of wall-paper has passed through the machine, the same is cut off and pasted on the wall. A release z^4 is embodied in the indicator, which returns the dial to the first graduation-mark.

In the described manner I have produced 25 a wall-paper seam-cutting and pasting machine which occupies little room and dispenses with the long boards or tables heretofore employed and is conveniently carried from the shop to any house. The machine 30 pastes the wall-paper in practically half the time heretofore used, and the coating of paste is perfectly uniform.

Having thus described my invention, I claim as new and desire to secure by Letters

35 Patent—

1. A wall-paper seam-cutting and pasting machine comprising an oblong rectangular box with special space in its rear portion for the roll of wall-paper, an opening in its top 40 front portion, and a raisable oblong frame on its top hinged thereto on one side, seam-cutting devices mounted in the rear of said frame, a pair of guiding-rollers near the cutters, of which the top one is mounted on the frame, a set of three rollers consisting of a top roller 45 mounted on the frame, a roller below same and in contact therewith and a roller near the bottom of the box, a paste-carrying endless piece of cloth on the two last-named rollers, 50 gear-wheels secured one to one end of each of the four top rollers located outside of the box, a drive-wheel with crank-handle gearing with the two lower tooth-wheels, an indicator with pinion gearing with the drive-wheel, and guiding-rods passing through the 55 opening in the top front portion of the box.

2. In a wall-paper seam-cutting and pasting machine, an oblong rectangular box, a special space in its rear portion for the roll of 60 wall-paper, an opening in its front portion, a raisable oblong frame on its top hinged thereto on one side, a pair of guiding-rollers in the rear of the box the top one of which is mounted on the frame, a set of three rollers 65 consisting of a top roller mounted on the frame, a roller below same and in contact

therewith and a roller near the bottom of the box, a paste-carrying endless piece of cloth on the two last-named rollers, gear-wheels one secured to one end of each of the four 70 top rollers located outside of the box, a drive-wheel with crank-handle gearing with the two lower tooth-wheels, a device for indicating the number of feet of wall-paper run through the machine having a pinion which 75 gears with the drive-wheel, and guiding-rods passing through the opening in the front portion of the box.

3. In a wall-paper seam-cutting and pasting machine, an oblong rectangular box, a special space in its rear portion for the roll of wall-paper, an opening in its front portion and a raisable oblong frame on its top hinged thereto on one side, a metal bar secured to 80 said frame, incisions therein and cutting devices in said incisions consisting of a rotatable cutting-disk with pinion mounted in a fork-like frame, a forward extension on the lower end of one member of the frame, a pinion thereon, a movable iron bar located on 85 the inside of the rear wall of the box and on a level with same, adjustable stationary cutter-blades thereon, one for each cutting-disk, a spring on one end of the bar, a metal handle at the end of the movable bar pivoted to 90 the side wall of the box and having an extension overlapping the top frame, a pair of guiding-rollers near the cutting devices the top one of which is mounted on the frame, 95 gears thereon engaging the pinion on the extension of the fork-shaped cutter-frame, a drive-wheel with crank-handle, and tooth-wheels on the one side of the rollers in gear with the drive-wheel.

4. In a wall-paper seam-cutting and pasting 100 machine, cutting devices mounted in the rear top portion of same, comprising a metal bar, incisions therein consisting of a rotatable cutting-disk with pinion mounted in a fork-like frame, a forward extension on the lower 105 end of one member of the frame, a pinion thereon, a movable iron bar located on the inside of the rear wall of the box and on a level with same, adjustable stationary cutter-blades thereon one for each cutting-disk, 110 a spring on one end of the bar, a metal handle at the other end of the movable bar pivoted to the side wall of the box and actuating 115 said movable bar.

5. In a wall-paper seam-cutting and pasting 120 machine, an oblong rectangular box representing the paste vessel, an opening in its top front portion, guiding-rods extending through said opening, a set of three rollers 125 consisting of a smooth top roller, a second roller below same, a third roller near the bottom of the box, a paste-carrying endless piece of cloth on the second and third rollers in contact with the top roller, gear-wheels one secured to one end of each of the first and 130 second rollers and located outside of the box, a drive-wheel with crank-handle secured on

the side of the box and gearing with the lower tooth-wheel, a ratchet-wheel on the axle of the drive-wheel, a spring-pawl engaging the teeth of said ratchet-wheel and a device with 5 a pinion gearing with the driving tooth-wheel and indicating the number of feet of wall-paper running through the machine.

Signed at New York, N. Y., this 26th day of June, 1903.

JOSEPH VOGT.
